UNITED STATES PATENT OFFICE.

JULIUS BERGOFF, OF BUFFALO, NEW YORK, ASSIGNOR TO EMPIRE JEWELRY CASE COMPANY, OF BUFFALO, NEW YORK, A CORPORATION OF NEW YORK.

METHOD OF MAKING PAPER BOXES.

SPECIFICATION forming part of Letters Patent No. 793,041, dated June 27, 1905.

Application filed August 24, 1904. Serial No. 221,912.

To all whom it may concern:

Be it known that I, JULIUS BERGOFF, a citizen of the United States, residing at Buffalo, in the county of Erie and State of New York, have invented new and useful Improvements 5 in Methods of Making Paper Boxes, of which the following is a specification.

This invention relates to the manufacture of boxes, and more particularly to round-cornered jewelry boxes or cases. Heretofore such jewelry-cases have been made of wood by constructing a square-cornered box, gluing filling-blocks in its corners, and then rounding the corners by cutting or trimming 15 off the surplus stock. Aside from the cost of the wood this method of manufacture renders such cases comparatively expensive.

The object of my invention is to devise a simple method by which a strong box or case 20 of this kind can be cheaply constructed of paper or pasteboard.

In the accompanying drawings, Figure 1 is a perspective view of the laminated band forming the sides of the box produced by my 25 improved method. Fig. 2 is a perspective view of the box, showing the bottom board glued thereto and the top board separated therefrom. Fig. 3 is a longitudinal central section of the box and the expansible former 30 placed therein. Fig. 4 is a top plan view of the box and the former.

Similar letters of reference indicate corresponding parts in the several figures.

Boxes or cases of the kind above referred 35 to are usually oblong and have rounded corners, and the cover is generally deeper than the body of the box. In producing such a box according to my improved method an approximately circular band A, of paper or 40 pasteboard, is first formed, preferably by gluing two or more strips of pasteboard a one upon another, so as to form a laminated band having about the thickness of the walls of ordinary wooden jewelry-cases. This endless 45 band forms the walls or sides of the box. As shown in the drawings, the strips of the band are laid upon one another so as to break joints. The glue which unites the strips moistens and

softens the same, and while the glue is still soft the band is stretched into oblong or rectangular form preferably with straight sides and ends and rounded corners by means of an expansible former placed within the band and having the proper contour and dimensions to form a box of the desired size and 50 shape, as shown in Figs. 3 and 4. The preferred former shown in the drawings consists of a pair of similar rectangular blocks B B, having straight sides and ends and rounded corners b and toggle-bars C C, connected by a 55 hinge c and adapted to bear at their outer ends against opposing transverse shoulders d of the blocks, so that upon straightening the toggle-bars, as shown by full lines in Fig. 3, the blocks are farther separated, thereby 60 stretching the band A and causing it to conform closely to the contour of the blocks. The thickness of the blocks is preferably 65 somewhat less than the width of the band A, and in order to center the blocks in the band 70 a space-plate e of the proper thickness is temporarily placed in the band between the bottom of the blocks and the work bench or table, so as to raise the blocks above the lower edge of the band, as shown in Fig. 3. 75 While the band A is in its stretched condition a bottom F, preferably of paper-board, is glued to one edge thereof, as shown in Figs. 2 and 3, and when the glue has become dry or set the former B is collapsed and removed 80 from the band by deflecting the toggle-bars C, as shown by dotted lines in Fig. 3. A top G, preferably of paper-board, is next glued to the opposite edge of the band A, and the two boards are then trimmed flush with the 85 band, and the edges of the case may be beveled or rounded, as in wooden jewelry-cases. The closed case so formed is next divided lengthwise by sawing or cutting the board upon the dotted lines shown in Fig. 2, thus 90 forming the body and the cover of the jewelry-case, and finally the two box members are suitably covered, ninged together, and finished in the ordinary manner. The stretching of the band causes its layers to be tightly 95 drawn against one another, thereby condens-

ing the fibers thereof and rendering the sides of the box much stronger and firmer than those of a box formed by winding a strip of paper around a solid or non-expandable form, 5 according to one of the methods hitherto practiced. As one of the boards F G is secured to the band before the former-blocks B are removed therefrom, the band is reliably retained in its stretched form by the board.

10 My improved box or case can be produced at much less cost than the wooden jewelry-cases heretofore employed, and it possesses greater strength at the corners than such a case, as it is free from corner-joints.

15 For economy of manufacture both the body and the cover of the case are preferably constructed at the same time by using a band A of the proper width and dividing the same after applying the top and bottom boards

20 F G thereto, as hereinbefore described; but it is obvious that the body and the cover could be made separately according to my improved method by employing a separate endless band for each of the box members

25 and then gluing a board to one edge thereof to form either the top of the cover or the bottom of the body.

While this improved method is especially desirable for making round-cornered boxes 30 or cases, it is also applicable to the manufacture of boxes of other forms, the former-

blocks B being properly shaped to produce a box of the desired form.

I claim as my invention—

1. The herein-described method of making 35 paper-box bodies or covers, which consists in forming an endless paper band of the proper width, thickness and diameter, then stretching the band while in a soft and moist condition to the desired shape and dimensions, and 40 finally securing a board to one edge of the band while in its stretched condition, substantially as set forth.

2. The herein-described method of making 45 paper-box bodies or covers, which consists in forming a laminated endless band by gluing together a number of pasteboard strips, then stretching the band to the desired shape and dimensions by a suitable former placed therein while the glue is still soft, whereby the 50 layers of the band are tightly drawn against each other in the act of properly shaping the band, and finally securing a board to one edge of the band while in its stretched condition, substantially as set forth. 55

Witness my hand this 18th day of August, 1904.

JULIUS BERGOFF.
